KARL JOHAN THORSBY, OF OAKLAND, CALIFORNIA, ASSIGNOR TO CALIFORNIA CORRUGATED CULVERT COMPANY, OF OAKLAND, CALIFORNIA, A CORPORATION OF CALIFORNIA.

SHEET-METAL FLUME.

1,180,621.

Specification of Letters Patent. Patented Apr. 25, 1916.

Application filed May 3, 1915. Serial No. 25,394.

To all whom it may concern:

Be it known that I, KARL JOHAN THORSBY, a subject of the King of Norway, residing at Oakland, in the county of Alameda and State of California, have invented 5 certain new and useful Improvements in Sheet-Metal Flumes, of which the following is a specification.

My invention relates to sheet metal flumes, 10 its object being to provide a means to compensate for the longitudinal expansion and contraction of the flume, due to changes in temperature, and it has the following distinct advantages:—(1) The inner surface of 15 the flume is smooth and unbroken; (2) no solder or rivets, which would tend to weaken such construction, are used.

My invention consists essentially in a 20 flume section, circumferentially grooved, channeled, wrinkled, corrugated, creased or fluted outwardly from its inner surface, the inner recesses, depressions or valleys thus formed being filled with a suitable adhesive and elastic material, in such manner that the 25 interior smoothness of the flume is unbroken.

In the accompanying drawings—Figure 1 30 is a perspective view of one of my flume sections, showing it connected up with adjacent sections of the flume. Fig. 2 is a section, enlarged, on the line $x-x$ of Fig. 1.

1 is a sheet metal flume section, connected 35 to adjacent sections 2 by means of joints 3. The section 1 is circumferentially grooved, channeled, wrinkled, corrugated, creased or fluted in planes transverse to its axis. For 40 convenience I will term it fluting, the flutes taking as their best form a plurality of substantially rectangular ridges 5, extending outwardly from the general inner surface of the section, the bottom of the intervening 45 valley 4 terminating short of the general inner surface of said section. The depressions of these transverse flutes are filled with a suitable material 6, which is elastic, adhesive, and unaffected by the liquid transported 50 through the flume; as, for example, when water is carried by the flume, an asphaltic compound can be used for the elastic filling in the flutes. The filling 6, it will be seen also covers the inner surface of the 55 intervening valley 4, and the level of said filling continues the smooth, unbroken inner surface of the section.

The section 1, with its transverse flutes, is 55 used in connection with the usual smooth

flume sections 2, and is joined to them by means of any suitable coupling or joint. These joints are shown as of a type now well known, comprising an inner compression member 7, outer clamping members 8, 60 and hanger plates 9, and these joints may be filled with the elastic material, as shown at 10, to preserve the smoothness of the interior of the flume.

When the metal of the flume expands 65 or contracts, on account of temperature changes, the longitudinal strains thereby set up are absorbed by the distortion of the walls of the flutes and the elastic material 6 within them. By interposing such fluted 70 sections at suitable intervals along a flume, all longitudinal expansion and contraction will be properly absorbed.

The flutes may have any form in cross section, but the particular form here shown, 75 namely substantially rectangular, is deemed best, in that the walls tend more easily to yield to expansion and contraction. There is thus a maximum flexibility enabling the walls of the flutes to readily yield to the 80 longitudinal motion of the flume.

The plural form of flute with intervening 85 relatively shallow valley is more practical in manufacture as having less tendency to crack the metal or its galvanized coating at 90 the corners. Moreover, this form, by affording opportunity for a continuous mass of filling in contradistinction to separate masses, as would be the case if the intervening valley 4 were as deep as the valleys of 95 the ridges 5, tends to a more uniform distribution of any rise or inequality which may take place in the inner surface of the filling, due to movement of the flute walls toward each other, thereby decreasing the 100 tendency to undue roughness or inequality in the flume interior.

With sections such as 1, having the elastic filling in its flutes, the inner surface of the flume is entirely smooth and free from 105 depressions or obstructions which would cause friction of the flowing water; and furthermore, the flutes being directly impressed in the metal sheet itself, rivets and solder are avoided, and this has proven to 110 be an important factor in sheet metal flume construction.

I claim:—

1. In a sheet metal flume, the combination 110 of a series of smooth flume sections; a flume

section having circumferential flutes extending outwardly from its inner surface; elastic material filling the interior depressions of said flutes to the level of the inner surface of the section; and means for joining the ends of said fluted section to the adjacent ends of the smooth flume sections.

2. In a sheet metal flume, the combination of a series of smooth flume sections; a flume section having circumferential flutes extending outwardly from its inner surface, said flutes being of substantially rectangular form in cross section; elastic material filling the interior depressions of said flutes to the level of the inner surface of the section; and means for joining the ends of said fluted section to the adjacent ends of the smooth flume sections.

3. In a sheet metal flume, the combination of a series of smooth flume sections; a flume section having circumferential flutes extending outwardly from its inner surface; elastic material filling the interior depressions of said flutes to the level of the inner surface of the section to preserve a smooth interior therefor; and couplings for joining the ends of the fluted flume section to the adjacent ends of the smooth flume sections, said couplings lying outside the circle of the general inner surface of the flume and having in their interstices a filling the inner surface of which is on a level with and continues the smooth interior of the flume.

4. In a sheet metal flume, the combination of a series of smooth flume sections; a flume section having circumferential flutes extending outwardly from its inner surface, said flutes being of substantially rectangular form in cross section; elastic material filling the interior depressions of said flutes to the level of the inner surface of the section to preserve a smooth interior therefor; and couplings for joining the ends of the fluted flume section to the adjacent ends of the smooth flume sections, said couplings lying

outside the circle of the general inner surface of the flume and having in their interstices a filling the inner surface of which is on a level with and continues the smooth interior of the flume.

5. In a sheet metal flume, the combination of a series of smooth flume sections; a flume section fluted with plural circumferential ridges extending outwardly from the inner surface, the intervening exterior valley between said ridges being of less depth than the height of the ridges; elastic material filling the depressions of said ridges and covering the inner surface of the floor of the intervening valley, said filling being carried to the level of and continuing the smooth unbroken inner surface of said section; and means for joining the ends of said fluted section to the adjacent ends of the smooth flume sections.

6. In a sheet metal flume, the combination of a series of smooth flume sections; a flume section fluted with plural circumferential ridges extending outwardly from the inner surface, the intervening exterior valley between said ridges being of less depth than the height of the ridges, both ridges and intervening valley being of substantially rectangular form in cross section; elastic material filling the depressions of said ridges and covering the inner surface of the floor of the intervening valley, said filling being carried to the level of and continuing the smooth unbroken inner surface of said section; and means for joining the ends of said fluted section to the adjacent ends of the smooth flume sections.

In testimony whereof I have signed my name to this specification in the presence of two subscribing witnesses.

KARL JOHAN THORSBY.
